TEMPERATURE CONTROLLING DEVICE

Victor L. Ronci, Brooklyn, N. Y., assignor to Bell Telephone Laboratories, Incorporated, New York, N. Y., a corporation of New York

Application March 31, 1933, Serial No. 663,766

12 Claims. (Cl. 49—81)

This invention relates to temperature controlling devices and more particularly to thermal contact switches or thermostats.

In the usual thermostat one or more contacts are sealed through the wall of the vitreous container and are exposed in the fine bore capillary to an expansible conducting body such as mercury, in order to establish an electrical circuit of which the expansible body is a part. Serious difficulties are encountered if the contact or contacts project into the capillary so as to reduce the cross-section thereof. Under such a condition adhesion of mercury to the contacts results in breaking the column of fluid and rendering the device inoperative. Another difficulty is the sealing of the contacts in the glass. This operation requires a skilled worker in order to insure alignment of sections of the capillary during sealing and accurate positioning of the contacts in order to obtain a required exposure of the contacts in the capillary bore. These difficulties increase the cost of thermostats due to the large loss in time and waste material.

An object of this invention is to facilitate the manufacture of thermostats whereby the contacts may be sealed in by a machine.

Another object of the invention is to insure adequate contact surface with the mercury in the capillary bore without causing blocking by adhesion.

In accordance with this invention a vitreous tube having an axial capillary bore communicating with a chamber or reservoir at one end containing an expansible conducting fluid such as mercury and at the other end terminating in an expansion chamber, is cut or severed transversely at a desired position in the capillary bore and a perforated flat contact sealed between the severed sections of the capillary with the perforation in the contact offset with respect to the axes of the capillary sections. A leading-in wire is also sealed in the end of the reservoir and is continuously in contact with the body of mercury therein. Expansion of the mercury due to elevating temperatures will cause the mercury to ascend in the capillary portion and conductively close an electrical circuit which is connected to the contacts of the thermostat.

Since the capillary portion of the thermostat must be severed in order to insert and seal the contact therein, visual precision must be practised by a highly skilled glass artisan in order to attain accurate alignment of the capillary bore of the two sections of the vitreous tube while insuring adequate protrusion of the contact into

the capillary bore so that the mercury will engage the contact. In accordance with this invention these difficulties are overcome by a method of assembly which can be accomplished by machine without the aid of skilled workers. This method consists in arranging the two sections of the cut capillary tube and the perforated contact between the sections and threading a guide member through the capillary bore and contact to maintain these details in position. This assembly is inserted in a revolving head of a sealing machine and the contact sealed between the sections of the capillary tubing. After cooling the guide member is removed, the mercury injected and the tubing sealed off to complete the thermostat.

The perforated contact insures positive contact surface in the capillary bore since the probability range of obtaining adequate contact is increased by the circular edge of the contact member. If the glass flows over the edge of the contact at certain points during the sealing process the probability of the glass flowing to entirely embed the contact is extremely remote.

The various features of the invention will be more clearly understood from the following detailed description in connection with the accompanying drawing:

Fig. 1 is a perspective view of a thermal element made in accordance with this invention showing the assembly of the contact member in the capillary portion;

Fig. 2 shows in perspective the positions of the separate parts of the thermal element prior to assembly;

Fig. 3 is a vertical cross-sectional view of the parts shown in Fig. 2 illustrating the alignment of the sections of the casing and the contact with the aid of a guide member preparatory to sealing the contact between the sections;

Fig. 4 is an enlarged cross-sectional view on the line 4—4 of Fig. 3 showing an exaggerated relation of the sizes of the capillary bore and the aperture in the contact; and

Fig. 5 illustrates a modification of the thermal element of this invention in cross-section with a number of contacts sealed in the capillary section.

Referring to the drawing, the thermostat shown in Fig. 1 comprises a length of common white-back capillary tubing forming the receptacle or casing 10 having a reservoir 11 containing an expansion fluid such as mercury 12. The closed end of the reservoir is provided with a leading-in wire 13 which is in contact with the mercury body 14.

in the reservoir and forms one terminal for establishing an electrical circuit. The reservoir 11 communicates with a fine bore capillary 14 which terminates in an expansion chamber 15 located at the opposite end of the device.

The contact 16 is sealed in the capillary 14 at a predetermined point and forms a second terminal for an electrical circuit. The location of the contact 16 depends upon the temperature at which the operation of the thermostat is desired. For instance, if the thermostat is to be operated when a temperature of 60° F. is attained, the contact 16 is sealed in the capillary at a point determined by the size of the capillary bore, length of the bore, the area of the reservoir and the amount of liquid contained in the reservoir. Consequently when the thermostat is within a heated enclosure, the gradual increase in temperature therein causes mercury to expand and rise in the capillary bore until at the temperature of 60° F., the mercury comes into engagement with the contact 16 and the electrical circuit is completed to operate a suitable relay or signal device.

The contact 16 in accordance with this invention is a metallic ribbon, preferably platinum, having an aperture 17 slightly larger than the capillary bore and when sealed in the glass bore of the capillary portion presents an extended surface of arcuate form to the column of mercury entering the capillary bore. This form of contact insures an adequate surface because the probability of the glass flowing over the entire edge of the aperture in the contact during the sealing-in process is remote. Furthermore, the edge of the contact exposed in the capillary bore is not of sufficient depth to separate the column of mercury. This difficulty is quite prevalent with the usual wire type of contact.

The method of making thermostats and sealing-in the contact will now be described with reference to Figs. 2 and 3. A length of common spirit white-back capillary tubing having an outside diameter of .195 inch and inside diameter of .007 inch is heated in a glass-blower's flame and an expansion chamber 15 is blown adjacent one end thereof. Then the other end of the tubing is heated in a similar manner to form the reservoir 11.

Intermediate the reservoir and the expansion chamber is a definite length of capillary bore 14 in which the contact 16 is to be positioned to be engaged by the mercury column. In order to make the seal, it is necessary to separate the capillary tubing and this is conveniently done by breaking the tubing sharply at a point at which it is desired to place the contact. The breaking of the tubing avoids variations of the contour and diameter of the capillary bore since it is obvious any other method of separation may change the shape of the bore. After the capillary tubing is separated, a guide member or wire 18, such as a molybdenum wire having a diameter of .005 inch is threaded through the sections having the expansion chamber 15, the wire being inserted through the end of the tubing adjacent the chamber 15 and then extending through the bore 14. The guide wire is then inserted through the aperture 17 in the ribbon contact 16. The diameter of the aperture is, for example, .012 inch and the thickness of the contact may be one mil. The guide wire is finally threaded through the other section of capillary tubing, first entering the bore 14 and then extending through the open reservoir 11.

The assembled details are now in position to

be placed in a rotary head of a glass sealing machine, provision being made to hold the sections of tubing against individual movement and the ends of the guide wire being held under tension to insure an accurate alignment of the capillary sections and the contact on the guide rod. After the details are placed in position in the head of the machine the two sections of tubing are adjusted to align the white backing in the tubing and to fit the two faces of the broken tubing in order that the glass grain may be properly aligned. The contact is positioned in the center of the white backing intermediate the longitudinal edges thereof and the end of the contact projecting from the side of the capillary tubing is tensioned slightly to cause the inner edge of the aperture 17 away from the point of applying the tension to engage the circular surface of the guide wire 18. The tension applied to the contact, however, is not so great as to misalign the guide wire. This results in the aperture in the contact being eccentrically arranged with respect to the capillary bore and the wire 18.

Now the details are prepared for sealing the contact between the glass sections of tubing. The head of the machine is rotated in a well-known manner and a single stationary burner flame on the machine is directed toward the position of the break between the tubing. The burner flame is adjusted to a fine point in order to limit the area of glass which is subjected to heating to form the seal. The flame applied to the rotating assembly causes the glass to soften and weld together at the break and hermetically seal the contact in place. During the sealing of the contact in the glass, a diatomic gas, such as nitrogen, is continually passed through the capillary tubing to prevent oxidation of the molybdenum guide wire and also to prevent the collapse of the glass.

After the sealing operation is completed, the guide wire is removed and this is effectively accomplished by stretching the wire 18 to the breaking point and the two pieces of wire are drawn out of the capillary bore. The breaking of the guide wire avoids kinks or bends in the wire which might score the capillary bore.

When the guide wire is removed from the capillary tubing the seal is annealed by heating to a temperature of 465° C. for one half hour by a soft flame, such as a flame without air or gas pressure, and then cooled for two hours. The heating and cooling produce a proper annealing treatment to offset cracking of the glass in subsequent operations. This annealing treatment also removes any molybdenum oxide which may have adhered to the wall of the capillary bore. The capillary tubing is removed from the machine and cleaned thoroughly in an acid bath and then in a distilled water bath to remove any particles of foreign matter from the capillary tubing. After the cleaning operation, the end of the tubing containing the reservoir is closed by forming the glass on the end of the reservoir and piercing the closure by forming a central aperture to receive a wire contact 13 which is hermetically sealed in position as shown in Fig. 1.

The completion of the sealing operation of the contact in the capillary tubing prepares the thermostat for the filling operation. The capillary tubing is attached to an exhausting system and heated in an oven to remove water vapor and highly evacuated to remove contaminating

vapors or air in the vessel. After the device is exhausted, a regulated quantity of mercury is injected into the capillary bore and substantially fills the reservoir 11. It will be evident that the 5 mercury is mechanically and electrically in contact with the terminal 13 in the end of the reservoir. Prior to sealing off the end of the thermostat from the exhausting system an inert gas, such as argon, is injected into the capillary bore, 10 at a pressure equal to atmospheric. The purpose of the gas is to prevent the separation of the column of mercury since the head pressure of gas insures the mercury being maintained in a continuous column. However, when the column 15 of mercury is elevated in the capillary bore, the increased pressure of the gas is negligible and does not cause irregular action of the mercury nor cause an incorrect indication of temperature.

It will be apparent from Fig. 4 that the arcuate 20 surface 20 exposed in the capillary bore of the tubing presents an extended surface to the rising column of mercury and does not project too far into the capillary bore to cause separation of the column of mercury. It will be evident that the 25 arcuate surface of the contact in the capillary bore precludes the possibility of glass, during the sealing operation, completely flowing over all the edge of the contact exposed in the capillary and consequently if some of the edge is entirely embedded by the glass there is still sufficient surface 30 exposed in the capillary to form an efficient contact.

It is of course understood that variations of 35 the diameter of the capillary bore in the tubing will necessitate a change in the diameter of the aperture in the contact 16. The invention may also be practised in a thermostat in which multiple contacts are arranged in the capillary bore to accommodate the thermostat to a wider 40 range of control. For instance, as shown in Fig. 5 the three contacts 21, 22 and 23 which are similar to the contact 16 described in the other figures may be arranged at elevated positions in the capillary tubing and sealed-in simultaneously by the method described herein. It is also 45 apparent that the shape of the aperture in the contact need not necessarily be circular, but may assume other forms to carry out the object of this invention. Furthermore, various other features of the invention may be modified without changing the scope of the invention as defined in the appended claims.

What is claimed is:

1. A temperature controlling device comprising 55 a vitreous vessel having a capillary bore and a reservoir at one end thereof, a terminal extending into said reservoir, a body of expansible conducting material in said reservoir, and a metallic contact having a perforated portion eccentric with 60 respect to said bore sealed through the wall of said vessel, the perforated edge of said contact extending into said capillary bore to the extent of at least a 90 degree arc.

2. A temperature controlling device comprising 65 a vitreous vessel having a capillary bore and a reservoir at one end thereof, a terminal extending into said reservoir, a body of expansible conducting material in said reservoir, and a thin flat metallic contact having a perforation therein, a continuous portion of the perforated edge extending into said bore and the remaining edge of the perforation and the edges of the contact being embedded in said vessel.

3. A temperature controlling device comprising 75 a vitreous vessel having a capillary bore and a

reservoir at one end thereof, a terminal extending into said reservoir, a body of expansible conducting material in said reservoir, and a metallic contact having an annular portion sealed in the wall of said vessel, the axis of said annular portion being eccentric with respect to the axis of said capillary bore.

4. A temperature controlling device comprising 10 a vitreous vessel having a capillary bore and a reservoir at one end thereof, a terminal extending into said reservoir, a body of expansible conducting material in said reservoir, a contact extending through the wall of said vessel and having a portion exposed in said capillary bore, and a filling of inert gas in said capillary bore.

5. A temperature controlling device comprising 15 a vitreous vessel having a capillary bore and a reservoir at one end thereof, a terminal extending into said reservoir, a body of mercury in said reservoir, a metallic contact extending into said vessel and exposed to said mercury in the capillary bore, and a filling of argon at atmospheric pressure in said vessel.

6. The method of sealing a metallic contact in 20 a capillary vitreous vessel which comprises, separating said vessel transversely in the vicinity of said capillary, piercing a contact to provide an aperture substantially corresponding to the diameter of said capillary, assembling the separated portions of the vessel with the apertured contact 25 therebetween on a guide member, sealing said contact in said separated portions, and removing said guide member.

7. The method of sealing a metallic contact in 30 a capillary vessel which comprises, separating 35 said vessel transversely in the vicinity of said capillary, forming an aperture in the contact substantially corresponding to the diameter of the capillary, assembling the separated portions of the vessel with the apertured contact therebetween on a guide member, sealing said contact 40 to locate the aperture therein eccentric with respect to the capillary, sealing the contact in the vessel, and removing said guide member.

8. The method of sealing a metallic contact in 45 a capillary vessel which comprises, separating 50 said vessel transversely in the vicinity of the capillary, forming an aperture in the contact substantially corresponding to the diameter of the capillary, assembling the separated portions of the vessel with the apertured contact therebetween on a guide member, sealing the contact in the vessel, stretching the guide member to the breaking point, and removing the parts of the 55 member from opposite ends of the capillary.

9. The method of sealing a metallic contact in 60 a capillary vessel which comprises, separating 65 said vessel transversely in the vicinity of said capillary, forming an aperture in the contact substantially corresponding to the diameter of the capillary, assembling the separated portions of the vessel with the apertured contact therebetween on a guide member, sealing said contact 70 in the separated portions of the vessel, and injecting a flow of a non-oxidizing gas in the capillary during the sealing operation.

10. The method of sealing a metallic contact 75 in a capillary vessel which comprises, separating 80 said vessel transversely in the vicinity of said capillary, forming an aperture in the contact substantially corresponding to the diameter of the capillary, assembling the separated portions of the vessel with the apertured contact therebetween on a guide member, sealing the contact 85 in the vessel, passing nitrogen through the capillary 90

illary during the sealing operation, removing the guide member, annealing the seal, evacuating the vessel, filling the vessel with an expansible liquid, injecting argon gas after the liquid filling, and finally sealing said vessel.

- 5 11. In the manufacture of a temperature controlling device having a capillary vessel terminating in an enlarged chamber at one end and having contacts in the chamber and capillary portion, the method which comprises separating said vessel transversely in the vicinity of said capillary, 10 forming an aperture in a contact substantially corresponding to the diameter of the capillary, assembling the separated portions of the vessel with the apertured contact therebetween on a guide member, sealing the contact in the vessel, 15 passing nitrogen through the capillary during the

sealing operation, removing the guide member, annealing the seal, evacuating the vessel, filling the vessel with an expansible liquid, injecting argon gas after the liquid filling, and finally sealing said vessel.

- 5 12. A temperature controlling device comprising a vitreous vessel having a capillary bore and a reservoir at one end thereof, a body of expansible liquid in said reservoir, and an eccentric metallic contact having a perforation with a continuous edge sealed through the wall of said vessel, said contact having an arcuate portion extending into said capillary bore to the extent of at least a 90 degree arc.
